UNITED STATES PATENT OFFICE.

WILLIAM J. MALONEY, OF ANSONIA, CONNECTICUT.

NARROW-FABRIC-LOOM SHUTTLE.

1,411,639.

Specification of Letters Patent. Patented Apr. 4, 1922.

Application filed August 4, 1921. Serial No. 489,789.

To all whom it may concern:

Be it known that I, WILLIAM J. MALONEY, a citizen of the United States, residing at Ansonia, county of New Haven, State of Connecticut, have invented an Improvement in Narrow-Fabric-Loom Shuttles, of which the following is a specification.

This invention relates to loom shuttles and particularly narrow fabric loom shuttles such as are used for the manufacture of suspender wedding, tapes, ribbon, surgical webbing, garter and armband webbing, elastic frill web and so forth.

An object of the invention is to yieldingly place the filling or weft yarn in the webbing or ribbon, so as to break the sudden throw of the thread in the shuttle against the edge of the web.

It is also an object of the invention to provide a shuttle which may be adjusted to give a tight or round edge on one side and a loose or frill edge on the other side.

It is a further object of the invention to provide a shuttle which may be adjusted to make two round edges exactly alike.

In my preferred construction these objects are accomplished by mounting a shuttle eye or guide in a ball yieldingly mounted in the grooved front part of the shuttle and also providing adjustable means by which the ball and the eye can be made stationary at any point within the slot in the front part of the shuttle.

In connection with a more detailed description of the invention reference is had to the accompanying drawings illustrating the preferred form thereof, and in which;

Fig. 1 is a plan view of a shuttle comprising my invention;

Fig. 2 is a transverse central section thereof;

Fig. 3 is a longitudinal central section;

Fig. 4 is a front edge view;

Fig. 5 is a detail perspective view of one of the adjustable stops for the ball, and

Fig. 6 is a sectional view of the ball.

In the form of shuttle illustrated, the body 10 thereof is provided with a bowed front portion 11, the usual guide 12 for the shuttle block, and the rack 13. Within the opening formed by the base and front portions of the body is mounted the bobbin or spool 14 which carries the supply of filling thread, it being mounted on the wire spindle

15 removably mounted in the shuttle in recesses at the opposite ends thereof in the

usual manner. In front and adjacent the opposite ends of a spool or bobbin are the guiding eyes 16 and 17 secured to the ends of light springs 18 and 19 mounted within the body. Mounted in back of the bobbin is a brake 20 bearing against the thread and pivotally mounted in the body at 21. This brake is pressed against the thread by means of a spring 22 and prevents the thread 60 unwinding too rapidly. The construction so far described is usual in this type of shuttle.

The front curved or bowed portion of the body is provided with two slots 23 and 24 and between the two within the front portion is mounted the ball 25. This ball fits loosely within the body portion so that it is free to turn therein and may move back and forth.

A guiding tube 26 extends diagonally through the ball to form a guiding eye for the thread. This tube is secured in the ball by any suitable means such as set screw 27. On substantially opposite diagonal points the ball is provided with eyes 28 and 29 to which are secured light coil 70

springs 30 and 31, these springs extending through suitable guiding tubes 32 to the base of the body portion where the other ends of the springs are firmly secured by any suitable means as wedges or plugs 30. 80

Within the bowed front portion of the body, on opposite sides of the ball, are adjustably mounted clamping and limiting rings 33 and 34. These rings are preferably made 85

of wire provided at one side thereof with two spaced parallel supports 35 bent substantially at right angles to the body of the ring and they may be strengthened by soldering at the bend 35 if desired. These supports are adapted to straddle screws 36 90

and 37 threaded into the inner wall of the closed portion adjacent the opposite ends of the slot 24. Beyond the screws, the body is provided with two openings 38 through which the free ends of the supports 35 may 95

extend. By loosening either or both of the screws 36 and 37, the rings 33 and 34 may be adjusted to and from the ball 25 and then clamped in adjusted position by tightening up these screws. Mounted upon the 100

inner end of the tube 26 is a thread guiding eye 39.

The shuttle is threaded by leading the thread T from the spool or bobbin 14 through the eye 39, yieldingly mounted 105

guiding eyes 16 and 17, and then through tube 26 from the inner end thereof emerging 110

from the outer free end at the front curved portion of the shuttle.

In operation, the clamping and limiting rings 33 and 34 may be adjusted to any position according to the effect desired. If they are spaced away from the ball 25, as shown in Fig. 3 of the drawing, the ball will be yieldingly mounted within the bowed front portion 11 by means of springs 30 and 31, and a tension either to the right or left will turn the ball accordingly or may move the ball bodily against one of the rings 33 or 34 according to the amount and direction of the pull thereon. It will be apparent that, if one of the rings 33 or 34 is spaced a greater distance from the central or neutral position than the other, that the guide or eye 26 will yield more when the shuttle is reversed at one end of its travel than at the other, thus giving different effects on the opposite edges of the fabric. It will be clear from this that, under the normal conditions where a stationary guide corresponding to the guides 26 is employed, nonuniform edges are liable to be produced. With my form of shuttle, adjustments may be made to counteract the unequal conditions to be met.

Again, if it is desired to form different edges on the opposite sides of the fabric, as for instance, a frilled edge on one side and a round edge on the other, one of the rings 34 may be advanced to prevent the shuttle ball 25 moving toward that side of the shuttle, but the other ring may be spaced away from the ball allowing it to yield toward this side.

Further, the shuttle may be employed the same as the present shuttles in which the guide or eye 26 is stationary in the center of the shuttle. This may be accomplished by moving the rings 33 and 34 toward the ball 25 and clamping it in the central position. It will also be apparent that by the same means the ball 25 may be secured stationary at any point within the curved front 11 by moving it to the position desired and then clamping it therein by means of the rings 33 and 34. An arrangement such as this will give a tight edge on one side and a loose edge on the other because, as the guide 26 is not in the center of the shuttle, the same throw is not obtained on the two sides because the shuttle travels the same distance each time.

In forming a frill edge with the shuttles at present employed in which the central guide or eye is stationary, an edge wire is usually required to hold out the edge while weaving because of the hard pull of the stationary guide or eye in said shuttle. With shuttles embodying the present invention, however, this wire is unnecessary in making a frill edge because as the eye or guide 26 is yieldingly mounted, it breaks the sudden throw

of the thread in the shuttle against the edge of the web. At the same time the filling is placed in the web at the same tension as it would with a stationary guide because of the tension springs 18 and 19. 70

Although I have disclosed the invention as embodied in the type of shuttle shown, it may be used equally as well in a circular shuttle.

Having thus set forth the nature of my 75 invention, what I claim is:

1. A loom shuttle comprising a body, a guide for the thread as it leaves the shuttle mounted in the front portion of the body, and means allowing adjustment of said guide 80 longitudinally of said front portion and for securing it in adjusted position.

2. A loom shuttle comprising a body, a guide for the thread as it leaves the shuttle adapted for longitudinal movement in the 85 front portion of the body, and means for adjustably and yieldingly mounting the guide.

3. A loom shuttle comprising a body having a bowed front portion, a guide for the 90 thread as it leaves the shuttle extending transversely of the bowed portion and adapted for movement longitudinally thereof, and yielding means for mounting the guide.

4. A loom shuttle comprising a body having a bowed front portion, a guide for the thread as it leaves the shuttle mounted in said bowed portion, and means allowing adjustment thereof longitudinally of said bowed portion and for securing the guide 100 in adjusted position.

5. A loom shuttle comprising a body having a bowed front portion, a guide for the thread as it leaves the shuttle, and means for adjustably and yieldingly mounting the 105 guide in the said bowed front portion, said guide being adapted for movement longitudinally of said bowed portion.

6. A loom shuttle comprising a body having a tubular curved portion, with slots in 110 the inner and outer walls thereof, and a ball loosely mounted in said tubular portion and guided thereby, provided with a thread guide.

7. A loom shuttle comprising a body having a tubular portion provided with longitudinally extending slots on opposite sides thereof, a ball loosely mounted in said tubular portion and guided thereby and provided with a thread guide, and adjustable 120 stops on opposite sides of said ball.

8. A loom shuttle comprising a body having a tubular portion, a ball loosely mounted in said tubular portion and guided thereby and provided with a thread guide, and 125 yielding means connected to said ball on opposite sides thereof.

9. A loom shuttle comprising a body having a tubular portion, a ball loosely fitting in said tubular portion and guided thereby and 130

provided with a thread guide, and springs attached to the ball on opposite sides thereof and to the body portion.

10. A loom shuttle comprising a body having a tubular portion, a ball loosely fitting in said tubular portion and guided thereby and provided with a thread guide, springs secured to the ball on opposite sides thereof and tending to move it in opposite directions, and adjustable limit stops on opposite sides of said ball.

11. A loom shuttle comprising a body having a tubular portion, a ball provided with a thread guide mounted in said tubular portion and adapted to have adjusting movements therein, and means for clamping said ball in any desired adjusted position.

12. A loom shuttle comprising a body having a tubular portion, a thread guide mount-

ed for longitudinal movement in said tubular portion and guided thereby, and means for securing the guide in any adjusted position.

13. A loom shuttle comprising a body having a tubular portion, a thread guide mounted for longitudinal movement in said tubular portion and guided thereby, yielding means connected to the guide on opposite sides thereof, and adjustable stops for limiting the movements of said guide.

14. A loom shuttle comprising a body having a guide extending longitudinally thereof, a thread guide mounted to move in said guide, and yielding means on the opposite sides of said thread guide and tending to move it in opposite directions.

In testimony whereof I affix my signature.

WILLIAM J. MALONEY.
